UNITED STATES PATENT OFFICE.

WALTER MATEER, OF MANSFIELD, OHIO.

SUSPENDERS.

1,214,569.

Specification of Letters Patent.

Patented Feb. 6, 1917.

Application filed August 4, 1915. Serial No. 43,675.

To all whom it may concern:

Be it known that I, WALTER MATEER, a citizen of the United States of America, residing at Mansfield, in the county of Rich-
5 land and State of Ohio, have invented cer-
tain new and useful Improvements in Sus-
pender, of which the following is a specifi-
cation.

This invention relates to suspenders and
10 especially to the type commonly known as
invisible suspenders.

The primary object of this invention is to
provide a suspender that will connect the
shoulder straps and the supporting straps in
15 such a manner as to afford a yielding con-
nection between them which will permit the
straps to automatically adjust themselves to
the various irregular movements of the body
20 of the wearer, thereby preventing undue
strain upon the straps and giving comfort
and ease to the wearer, irrespective of the
position or shape of the body.

Another object is to connect the shoulder
25 and supporting straps by a universal joint
which includes a method of interlacing sup-
plementary straps which are connected to
the shoulder straps and adapted to pass over
20 and travel on the rollers of the universal
joint to obviate undue friction.

30 A further object is to connect and ar-
range the shoulder straps and supporting
straps to afford facilities for slipping on the
suspenders upon the body of the wearer
after the fashion of a coat or the like.

35 A further feature of the invention is the
method of yieldingly connecting one end of
the shoulder and supporting straps to a com-
mon center preferably located at the median
line of the back of the wearer from which
40 point the combined straps radiate or diverge
to loop over the shoulders of the wearer
and also depend adjacent to the hips of the
wearer to be attached to the trouser for sup-
porting purposes.

45 Another object is to provide an invisible
suspender that will adjust itself automatic-
ally to support a trouser or the like equally
at all times and under all circumstances
50 thereof without undue or unequal strain
upon any of the parts comprising the sus-
pender.

I attain these and other objects by the

mechanism illustrated in the accompanying
drawing, in which:

Figure 1 is an enlarged rear elevation in
perspective of my invention showing the
universal joint connected to fragments of
the shoulder straps through the medium of
supplementary straps which engage the uni-
versal joint and the means of connecting
the universal joint to the supporting straps.
Fig. 2 is a front elevation in perspective of
the invention showing the suspender in po-
sition to slip on the wearer and the parts
thereof assembled and in their normal posi-
tion when the suspender is upon the body of
the wearer. Fig. 3 is a side elevation of
Fig. 2.

In the drawings, reference numerals 1 and
2 represent shoulder straps to one end of
which the supplementary reduced straps 3
and 4 are attached. Intermediate of the
ends of the shoulder straps 1 and 2, the sup-
plementary straps engage the rollers 5 and
6, the crown form of the faces thereof serv-
ing to maintain the movable supplementary
straps upon the central portion of the crown
rollers, thereby keeping the edge of the sup-
plementary strap from contacting with the
sides of the journal yokes to obviate undue
friction, permitting the supplementary
straps to movably respond to the pull or
draw of the shoulder and supporting straps
freely to conform and coincide with the
movement of the body of the wearer and
equalize the strain on the parts of the sus-
pender as contra-distinguished from the
strain produced when the straps comprising
the suspenders are connected together by a
non-movable joint.

The supplementary strap 4 is separately
fastened to the shoulder strap 1 by the tabs
7 which are disposed on each side thereof
and one end of the supplementary strap 4
95 interposed therebetween. The opposite end
of the supplementary strap 4 is interlaced
between the sides 8 and 9 of a yoke formed
with a journal upon which the roller 6 is
mounted and it is then fastened by the tabs
100 10 to the shoulder strap 2, making what
might be termed a straight movable belt
contact.

One end of the supplementary strap 3
is also interposed between, but underneath,
105 the supplementary strap 4 and is also fas-

2

tened to the shoulder strap 1 by the tabs 7. The opposite end is then crossed and interlaced between the sides 11 and 12 of an enlarged yoke formed with a journal which 5 inclose the yoke above referred to and is finally fastened to the shoulder strap 2 above the supplementary strap 4 interposed between and fastened to the shoulder strap 2 by the tabs 10, making a cross belt contact.

10 The above arrangements and method of connecting the shoulder straps in conjunction with the universal joint, provides a yielding and movable connection that obviates friction. The supporting straps 13 and 14 are connected to the journal yokes by a member 15 that is provided with a journal 16 that receives and pivotally journals the connecting members (not shown) of the yokes. The member 15 also rigidly fastens 15 and joins the supporting straps 13 and 14.

15 It will be observed that the above arrangements permit the straps to diverge and radiate from a common center to perform the functions intended as particularly 20 pointed out in the objects described herein.

25 A buckle 17 and loop connection 17' provide means for adjusting the shoulder straps to the height and body of the wearer. A button fastener 18 is preferably used to at-

tach the supporting and shoulder straps to 30 the trouser or the like, the supporting straps being looped to receive and fasten the hanger thereto.

Attention is called to the fact that the assembled suspender made up and arranged as 35 described, provides a skeleton coat-like form that makes it easy and convenient to slip on.

What is claimed is:

A two-point suspension suspender, comprising a pair of button fasteners, a pair of 40 rear straps connected together at their upper ends and looped adjacent their opposite ends, the looped portion of each strap passing through one of the button fasteners, a pair of front straps connected at their lower 45 ends to the looped ends of the rear straps at a point above the button fasteners, means carried by the connected ends of the rear straps, and a pair of straps connecting the upper ends of the front straps, and said 50 means for forming a yielding connection.

In testimony whereof I affix my signature in presence of two witnesses.

WALTER MATEER.
